(57) **CLAIM**

The ornamental design for a footrest pillow as shown and described.

DESCRIPTION

FIG. 1 is a perspective view of a footrest pillow showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof; and,

FIG. 9 is a partial enlarged view of portion 9 in FIG. 1. The broken lines depict portions of the footrest pillow and form no part of the claimed design. The dot dash broken lines depict areas of enlarged views and form no part of the claimed design.
